UNITED STATES PATENT OFFICE.

SAMUEL C. CARROLL, OF DALLAS, TEXAS.

DESIGN FOR A NUT-LOCK WASHER.

SPECIFICATION forming part of Design No. 31,714, dated October 24, 1899.

Application filed August 31, 1899. Serial No. 729,132. Term of patent 14 years.

To all whom it may concern:

Be it known that I, SAMUEL C. CARROLL, a citizen of the United States, and a resident of Dallas, Texas, have invented and produced 5 a new and original Design for a Nut - Lock Washer, of which the following is a specification, reference being had to the accompanying drawings, forming a part thereof.

In the drawings, Figure 1 is a perspective 10 view of the invention. Fig. 2 is a plan view of the same.

As shown in the drawings, the leading feature of my design consists of an annular disk A, having a depression a on the margin of its 15 inner opening and with an incision cut in

from the periphery, forming a tongue b, which is raised slightly above the face of the body portion.

Having thus described my invention, what I claim as new, and desire to secure by Letters 20 Patent, is—

The design for a nut-lock washer substantially as shown and described.

In testimony whereof I have hereunto set my hand, this 17th day of July, 1899, in the 25 presence of two witnesses.

S. C. CARROLL.

Witnesses:

F. L. MIDDLETON,

C. S. MIDDLETON.
